TIRE

William F. Billingsley, Silver Lake, Ohio, assignor to
The B. F. Goodrich Company, New York, N. Y., a corporation of New York

Application March 25, 1955, Serial No. 35,196

Term of patent 14 years

(Cl. D90—20)

Fig. 1 is a perspective view of a tire showing my new design;

Fig. 2 is a fragmentary section through the tire taken on line 2—2 of Fig. 1; and

Fig. 3 is an enlarged fragmentary view of the tread better illustrating the nature of the kerfs in the tread ribs.

The dominant features of my design reside in those portions shown in solid lines.

In Fig. 1 the dotted line disclosure is understood to represent the repetition of the design shown in full lines.

I claim:

The ornamental design for a tire, as shown and described
